UNITED STATES PATENT OFFICE

EDOUARD ARMELIN, OF LONDON, ENGLAND

CONSTRUCTION OF THE HOLDERS OF BOOK MATCHES

Application filed August 21, 1929, Serial No. 387,466, and in Great Britain August 10, 1928.

This invention relates to the construction of holders or folders employed as a sheath or cover for book matches, and the object of the invention is to provide an article of greater utility and capable of being used to a greater extent as an advertising medium than heretofore.

According to the invention there is provided a book match holder to which is applied a receptacle for interfolded papers, preferably provided with means for protecting the said papers from contact with the matches.

In carrying the invention into effect the inner face of the usual protective flap of a book match holder has applied thereto a receptacle or pocket designed to receive cigarette or other papers in interfolded relation and arranged to permit their withdrawal one at a time when required for use. The book match holder is provided with an additional flap preferably secured at or about the centre of the holder and adapted to overlap the match heads when the holder is closed so that the exposed portion of cigarette paper or the like is protected from contact with the match heads.

In order that the invention may be understood reference will be made to the accompanying drawing, in which:—

Figure 1 is an interior view of an open book match holder provided with a receptacle in accordance with the invention.

Figure 2 is a side elevation thereof.

Figure 3 is a central vertical section of Figure 1 on an enlarged scale and showing a book match holder in a closed position.

Figure 4 is a front elevation of a portion of the book match holder shown in Figure 1 with the receptacle provided with interfolded papers.

Figure 5 is a view similar to Figure 3 showing a modification thereof, and

Figure 6 is a vertical section through the pocket portion of the book holder illustrated in Figure 5 and showing interfolded paper in position.

Referring to the drawing, A is a book match holder of well known construction and

B is a receptacle applied thereto for the reception of interfolded papers.

The receptacle is preferably formed from a rectangular piece of card or the like 1, the four edges 2, 2, 2, 2, are turned under and mitred whereafter they are secured to the inner face of the holder cover flap 3, for example, by a suitable adhesive. The exposed face of the receptacle or pocket is provided with a slot 4 which extends between the two opposite sides thereof, and, as shown, centrally of the other two sides, and through which the interfolded papers or the like 6 are withdrawn from the pocket. An additional protective flap 5 advantageously comprising a strip of card or the like is secured along one of its longer edges adjacent to the line of match heads. The arrangement is such that when the holder is closed, as shown in Figure 3, the said strip of card 5 lies between the match heads and the portion of the outermost paper which is exposed.

The protective strip 5 may be formed as an extension of one of the turned under portions of the receptacle as shown in Figures 5 and 6, the said portion after being turned under being folded back upon itself to form the protective flap 5. It will be appreciated that such flap may simply be an extension of the receptacle, that is to say, without having a turned-under portion.

It will be appreciated that as the match heads are protected by the additional protective strip, the striking surface for the matches may be placed on the outer surface of the receptacle instead of placing the said striking surface on the exterior of the holder.

It will be realized that, instead of cigarette papers, sheets of paper bearing advertisements, for example, may be enclosed within the receptacle or pocket and adapted to be withdrawn, or such receptacle may be used for the reception of complexion powder papers, such as those known under the name of "Papier Poudre", for soap impregnated papers, perfumed papers and the like.

Claims:—

1. The combination with a book match holder having a cover flap, of a receptacle for papers carried on the inside face of the cover

flap, and means for protecting the papers from contact with the match heads, said means comprising a separate fibrous strip secured to said holder and extending between the match heads and the receptacle when the holder is closed and protecting the match heads when the holder is opened.

2. The combination with a book match holder having a cover flap, of a receptacle for papers carried on the inside face of the cover flap, and means for protecting the papers from contact with the match heads, said means comprising a fibrous strip extending between the match heads and the receptacle when the holder is closed.

3. The combination with a book match holder having a cover flap, of a receptacle for papers carried on the inside face of the cover flap, said receptacle comprising a fibrous sheet secured to the cover flap face, a portion of said sheet being extended and bent to interpose the same between the match heads and the receptacle.
